UNITED STATES PATENT OFFICE

CHARLES W. GORDON, OF PLEASANTVILLE, NEW YORK, ASSIGNOR TO THE SUPER-HEATER COMPANY, OF NEW YORK, N. Y.

BOILER

Application filed November 18, 1929. Serial No. 408,210.

This invention relates to boilers having connection. Such baffling includes in this case, as in prior cases, a horizontal baffle 16 extending from the rear end of the boiler to a point approximately at the middle of the housing; a second baffle 17 rising vertically 55

upward from the front end of the baffle 16 across the upper bank of tubes and terminating short of the roof of the housing; and a third baffle 18 extending downward from a point in the roof in front of the stack connection between baffle 17 and the rear of the housing and terminating at a point some distance 60 above the baffle 16.

The boiler, as stated above, comprises two banks of tubes 1 and 2. These tubes are inclined at the usual angle to the horizontal, but in the specification and claims hereto they will be referred to as horizontal tubes in accordance with ordinary practice. The upper bank comprises several times as many tubes 20 as the lower, although this is immaterial as far as my invention is concerned. The tubes are secured in front headers 3a and 3b and rear headers 4a and 4b, the tubes of the upper bank connecting the headers 3a and 4a and 25 those of the lower bank connecting the headers 3b and 4b. The headers 3b are connected to each other by means of the nipples 3c while the headers 4a and 4b are connected to each other by means of the nipples 4c. The upper 30 ends of the headers 3a are connected by means of a series of tubes 5 to the steam and water drum 6. The latter is connected with the upper ends of the headers 4a by means of the nipples 7. The boiler is enclosed in the usual housing 8 and under the boiler there is located 35 the furnace 9. The gases are allowed to escape from the boiler housing through the stack connection 10.

In the forward portion of the space between the two banks is located the superheater 12. This superheater is made of tubular elements whose ends are connected to the two headers 13 and 14. The header 13 is connected to the steam drum 6 by means of the pipe 15. 14 is the outlet header and suitable connections (not shown) are made from it to carry the steam to the point of consumption.

It is practically necessary to baffle a boiler of this type so as to give the gases a tortuous 50 path of travel from the furnace to the stack

My invention resides in the location and manner of supporting baffle 16. 65

Heretofore this baffle has usually been located on top of the lower bank, or somewhere in the lower bank. In some instances it has been placed in the lower portion of the upper bank, in which case the superheater 70 can, and usually does, extend through the entire space from front to back between the two banks. Each of these arrangements has its advantages. When the former one is used, i. e., the arrangement with the baffle in the 75 lower bank, some difficulties are encountered, particularly if the coal used is of low grade with ash of low fusion temperature. These difficulties are removed by my invention.

I provide a number of hanger rods 19 80 which extend at suitable intervals through the upper bank of tubes and which are supported in position by the plates 20, through which they extend and which rest on the top row of tubes of the upper bank, and nuts 85 21 screwed on the upper ends of the rods and resting on these plates. The lower ends of these rods carry the transversely extending bars 22. Hung from these bars 22 is a series of T-shaped bars 23 which are suspended 90 in a position parallel to the water tubes. On these T bars are suspended the bricks 24 which make up a baffle. The bricks have T-shaped slots and are slipped on and along the bars into position. 95

The baffle can by the means described be hung at any desired level between the two banks. Fig. 1 illustrates what I regard as an advantageous position. The entire lower bank of tubes is open for the passage of the 100

gases from the furnace, so that their velocity through this bank is low, this being very effective for preventing slagging. The same beneficial effect is therefore secured as far as absence of slagging is concerned, as if the baffle were at the bottom of the upper bank and yet the benefits of a high gas velocity over the superheater surface is retained.

The manner of supporting the rods 19 from the upper bank is, only illustrative. Other means may be used, such for example as those shown for supporting the header in application #325,258 filed on December 11, 1928 by J. F. Kavanah. Other variations can obviously also be made in my invention without departing from its spirit.

I claim:

1. In a boiler having two vertically spaced banks of horizontal tubes, the combination with said banks, of a baffle between and parallel to them and spaced from both of them, and supports for said baffle hung from tubes in the upper bank.

2. In a boiler having two vertically spaced banks of horizontal tubes, the combination with said banks, of a baffle between and parallel to them and spaced from both of them, the baffle being nearer to the lower bank than to the upper, and supports for said baffle, said supports including rods extending through the upper bank and plates engaged by them resting on the top tubes.

3. In a boiler having two vertically spaced banks of horizontal tubes, the combination with said banks, of a baffle between and parallel to them and spaced from both of them, the baffle being nearer to the lower bank than to the upper, and supports for said baffle, said supports including rods engaging members resting on tubes of the upper bank.

4. In a boiler, in combination, a bank of horizontal water tubes, a plurality of bars transverse to the water tubes and below them, means supporting said bars and engaging and supported by some of the water tubes, an alined series of bars parallel to the water tubes and suspended from the first-named bars, and fire-resisting blocks suspended from said second-named bars contacting with each other and forming a continuous baffle.

5. The combination set forth in claim 4, said second named bars having longitudinal horizontal opposite flanges along their lower edges, and said blocks being suitably slotted to slip on and hang from said flanges.

6. In a boiler, the combination of two spaced banks of horizontal tubes, rods extending through the upper bank, means to support said rods, said means engaging the top tubes of the upper bank, bars transverse to the water tubes suspended from the rods in the inter-bank space, a set of alined bars parallel to the tubes suspended from said first-named bars, said second bars having an in-

verted T-shaped cross-section, and firebricks contacting with each other to form a continuous baffle, said bricks being slotted so as to slip on and hang from said second bars.

CHARLES W. GORDON.
